INVENTOR,
August B. Larson,
By *Joseph A. Mullan*
Attorney.

UNITED STATES PATENT OFFICE.

AUGUST B. LARSON, OF INDIANAPOLIS, INDIANA.

VEGETABLE BIN.

Application filed January 12, 1925. Serial No. 1,760.

To all whom it may concern:

Be it known that I, AUGUST B. LARSON, a citizen of the United States, residing at Indianapolis, in the county of Marion and State of Indiana, have invented a new and useful Improvement in Vegetable Bins, of which the following is a specification:

My invention relates to an improved vegetable bin for use such as for holding 10 potatoes, onions, turnips, and the like, and has for its objects, the ventilation of the vegetables contained, the separation of dirt and refuse from the vegetables, the handling of the vegetables in quantities quickly 15 by a scoop rather than by hand in removing the contents from the bin, the prevention of damage to the contents by rats and the like, a construction of extreme simplicity permitting the use of all metal parts as may 20 be cleaned and disinfected without injury thereto, and a construction that may be built in quantity production at a very low cost, having neatness of appearance as well as being of valuable service in grocery 25 stores, restaurants, and similar agencies where vegetables must be held in quantities and transferred to other containers in small and varying lots.

I accomplish these and such minor objects 30 as may be apparent in the following description by the means as illustrated in the accompanying drawing, in which—

Fig. 1 is a perspective view of my improved vegetable bin with fragments removed to disclose the various details of construction; Fig. 2, a fragment of the bin with the door in its raised position preparatory to closing as shown by the solid lines, and the door further revolved and nearing 35 closure as indicated by the dash lines; Fig. 3, a fragment of the bin showing the door fully closed; and Fig. 4, an elevation in section of a fragment of a corner iron showing a pin attached thereto about which the 40 door is operated.

Like characters of reference indicate like parts throughout the several views.

I form a bin by the four walls 5, 6, 7, and 8, preferably of sheet metal, supported 50 by the angle-iron frame having the vertical corner pieces 9 extending downwardly to act as supporting legs. I provide a close fitting removable top 10, Fig. 1, here shown partly opened, as the upper enclosure of the bin, 55 but the under side or bottom of the bin is left open.

To retain the vegetables in the bin, I use a slatted platform composed of a plurality of slats 11 properly spaced apart to permit dirt and refuse to pass downwardly between and still retain the vegetables of usable size. The slats 11, are formed with a horizontal forward section and an upwardly inclined rear section, such that the vegetables striking the rear section will roll forwardly onto the horizontal section. The ends of the slats 11 are secured to front and back transverse ties 12 to prevent their displacement, and to so form the integral platform, which is held within the bin upon the lower frame-work of angle-irons 13 and 14, with the rear ends of the upwardly inclined slats bearing against the back wall 8 of the bin.

The front wall 5 is provided with an opening entering upon the slats 11. Above this opening, I secure the baffle 15 so as to extend backwardly and downwardly toward the inclined sections of the slats 11 leaving a throat therebetween such that only a limited quantity of the vegetables may reach the forward horizontal sections of the slats 11.

Immediately below the platform of slats 11, I place a shallow pan 16. Fig. 1, here shown partly withdrawn, so as to catch the dirt and refuse that may drop through between the slats 11 as the vegetables move thereon. The pan 16 is retained by means of the slides 17 formed of angle-iron and secured to the legs 9, one on each side, such that the pan 16 may be slidably withdrawn from the front side of the bin.

The opening in the front wall 5 has a door 18 for a closure and also for a chute or scooping platform when open as in Fig. 1. The door 18 has its inner edge or apron 23 resting directly upon the slats 11, substantially within the bin, and bears against the corner pieces 9 by its shoulders 19. Each side of the door 18 terminates in an upwardly, vertically extending side 20, which projects past and slidably contacts the outer, side faces of the corner pieces 9 and is secured thereto by means of the pin 21 engaging through the cam slot 22 formed in the side 20. The pin 21, Fig. 4, is formed with a head to retain the side 20.

The cam slot 22 in each door side has a curved central section approaching an arc of a circle, and has a straight slot extending outwardly from the curved portion of

the slot for the purpose of locking the door in the open and in the closed positions, Figs. 1, and 3.

It will be noted in Fig. 1, that the door 5 apron 23 rests upon the slats 11 and thereby presents a junction such that a vegetable scoop may be slid over the door and onto the slats without interference of the slat ends.

10 To close the door 18, it is first lifted vertically from the position as in Fig. 1 to the position as in Fig. 2, where the curved portion of the cam slot 22 is ready to engage the pin 21, whereupon, the door may 15 be tilted upwardly and pushed inwardly about the pin 21 as indicated by the dash lines, Fig. 2, and then completely closed by allowing the pin 21 to travel the length of the curved portion of the cam slot 22, 20 into its straight section, when the door will drop vertically downwardly and be locked in its closed position, as in Fig. 3. Further rotation of the door 18 about the pins 21 is prevented by reason of the front edge, 25 now the top edge, of the door 18 striking and bearing against the front wall 5 above the enclosed opening.

In the closed position, the apron 23, extends downwardly and over the pan 16 so 30 as to prevent the withdrawal of the pan when the door is closed. The pan 16 closes the entire under side of the bin, and when the door 18 is closed, rats and mice can not gain access to the vegetables within.

35 Having fully described my invention in the form now best known to me, and being aware that it is obvious to vary the structure without departing from the spirit of my invention, I do not desire to be limited 40 to the precise structure shown and described, nor any more than may be necessary, 45 stated by the following claims.

I claim:

1. A door for an opening in a side wall 45 of a receptacle, adapted to serve as a scoop board when in an opened position and having an inwardly extending apron, said door having each end terminating in a vertical side member, and having a cam slot in each 50 of said side members to engage about a retaining pin secured to said receptacle, said slot permitting the door to drop down and be locked thereby in an opened position and permitting the door to be raised and passed

from the opened position to the closed position to be dropped and thereby locked in said closed position. 55

2. In a bin open at the bottom and top and having a side opening, a slatted platform forming the bottom of the bin, said platform being inclined upwardly toward the back and having a horizontal section projecting to the lower edge of the side opening, a baffle above and directed toward the inclined end of the platform, a removable pan below the platform, a door for said side opening having an inwardly extending apron resting on said platform when in an opened position, vertically extending ends of said door, door supporting pins on said bin, said door ends each having a cam slot therethrough engaging said pins and said cam slot being formed with a central section to permit the door being passed from one position to another, and an extended slot from each end of the central slot to cause the door to be dropped downwardly as a locking means in both opened and closed positions. 60 65 70 75

3. In a bin open at the bottom and top and having a side opening, a slatted platform forming the bottom of the bin, said platform being inclined upwardly toward the back and having a horizontal section projecting to the lower edge of the side opening, a baffle above and directed toward the inclined end of the platform, a removable pan below the platform, a door for said side opening having an inwardly extending apron resting on said platform when in an opened position, vertically extending ends of said door, door supporting pins on said bin, said door ends each having a cam slot therethrough engaging said pins and said cam slot being formed with a central section to permit the door being passed from one position to another, and having an extended slot from each end of the central slot to cause the door to be dropped downwardly as a locking means in both opened and closed positions. 80 85 90 95 100

Signed at Indianapolis, county of Marion, State of Indiana, this the 9th day of January, 1925.

AUGUST B. LARSON.
